UNITED STATES PATENT OFFICE.

LEROY M. LEWIS, OF PHILADELPHIA, PENNSYLVANIA, ASSIGNOR TO OWEN B. LEWIS, OF BALTIMORE, MARYLAND.

ALARM CHECK-VALVE.

1,385,460.

Specification of Letters Patent. Patented July 26, 1921.

Application filed October 28, 1919. Serial No. 333,944.

To all whom it may concern:

Be it known that I, LEROY M. LEWIS, a citizen of the United States, and a resident of the city of Philadelphia, county of Philadelphia, State of Pennsylvania, have invented certain new and useful Improvements in Alarm Check-Valves, of which the following is a specification, reference being had to the accompanying drawing, forming a part hereof.

My invention relates to certain improvements in automatic fire extinguishing systems of the sprinkler type adapted to be installed in buildings or similar locations for protection against fires and has reference more particularly to the main check valve combined with an auxiliary valve adapted to control the flow of fluid to an alarm controlling mechanism intended to operate an alarm in indication of the opening of one or more of the sprinkler heads of the system upon the occurrence of a fire or similar cause.

This application is a continuation in part of my Patent No. 1,339,567 dated May 11, 1920, for alarm controlling mechanisms.

One of the objects of my invention is to provide an alarm check valve which will operate only upon the opening of a sprinkler head and upon the flow of extinguishing fluid through the valve casing and to provide therewith an auxiliary valve controlling the flow of fluid to the alarm controlling mechanism.

Another object of my invention is to pivotally mount the main check valve and the auxiliary valve upon the same axis in the main casing whereby each may move therein independently of the other but so related that the opening of the main check valve will cause an opening of the auxiliary valve upon the main flow of fluid through the valve casing.

Another object is to provide the main and auxiliary check valves with means to meet the requirements of the Fire Underwriters Laboratories in that the check valve and the auxiliary valve should both be loosely mounted to have independent pivotal movement with the clearance usually required, namely, that of about one sixteenth of an inch of radial clearance between the pivot element and the parts to turn thereabout.

Another object is to so construct the aux-

iliary valve that the same will be effectively opened at a predetermined time after the beginning of the opening of the main check valve.

A still further object is to so locate and arrange the main and auxiliary check valves in relation to each other that a greater range of adjustment for any amount of opening of the main check valve may be obtained whereby a greater degree of sensitiveness of operation as regards the operation of the alarm controlling mechanism is secured.

Other useful objects and advantages of my invention will more fully appear in the following specification and the accompanying drawing made a part hereof.

Referring to the drawing in which is illustrated one embodiment of my invention and in which similar reference characters are used to designate the corresponding parts:

Figure 1 is a view in vertical section of a preferred form of device with the valves in closed position;

Fig. 2 is a view in transverse section on the line 2—2 of Fig. 1 showing the main and auxiliary check valves and the parts connected thereto in top plan view;

Fig. 3 is a fragmentary front view of the valves taken in a plane perpendicular to that of the valves, and,

Fig. 4 is a vertical section of the auxiliary valve means.

Referring now more particularly to the drawing the device illustrated comprises an alarm check valve structure having a hollow casing or body portion 1 provided at one end with a supply inlet 2 and at its opposite end with a discharge outlet 3 both of which and the chamber of the casing being in axial alignment for providing a direct passage for the extinguishing fluid. The inlet 2 and outlet 3 are provided with annular flanges 4 and 5 respectively suitably secured as by bolts 6 and 7 to the flanges 8' of a supply pipe 8 and the flanges 9' of a discharge pipe 9.

Within the body portion of the casing is provided a transverse partition 10 of substantially annular form and preferably integral with the casing. The inner marginal portion of this partition is preferably arranged in a plane slightly inclined with respect to a normal to the longitudinal axis of the body portion 1. The body of the casing also may be provided with a threaded

opening 11 through one side of the casing for connection with a drain pipe (not shown).

The casing or body portion 1 is also provided with a laterally extending substantially cylindrical hollow extension 12 preferably integral therewith, the interior of this extension communicating with the chamber of the casing 1 on the outlet side of the main check valve. The outer end of this extension is suitably closed by a cover 13 which is suitably secured to the extension 12 as by bolts 14.

For the purpose of controlling the flow of the extinguishing fluid through the main passage between the supply and discharge there is arranged in the body portion or casing 1 between the annular partition 10 and the outlet 3 a substantially circular main valve or clapper 15 which is provided on its inner side with an annular marginal surface 16 which is proportioned and arranged to coöperate with an annular valve seat 17 which is threaded into the annular partition 10 and which is also provided with a comparatively narrow flat bearing edge 18 arranged in a plane also laterally inclined to a normal to the axis of the body or casing 1 and substantially parallel to the plane of the inner marginal portion of the partition 10 and against which edge the flat marginal under surface 16 of the valve 15 engages when the main valve is closed.

For the purpose of supporting the valve 15 with its flat marginal under-surface 16 coincident with the bearing edge 18 of the valve seat, as well as to oscillate with respect to its seat 18 about a fixed axis, the main valve is provided with arms 19, preferably integral therewith, projecting therefrom approximately in a plane therewith and toward the cover 13. The other ends of these arms are enlarged to form substantially cylindrical bearings or hubs 20 which are rotatable and loosely mounted, with a clearance 20', upon a cylindrical pivot pin or shaft 21 extending therethrough, the longitudinal axis of which may be coincident with the plane of the bearing edge 18 of the main valve seat 17 and substantially parallel to the plane of the flat end 22 of the extension 12 of the casing. The ends of the pivot pin or shaft 21 may extend and fit into suitable supporting means or bosses that may be located or integrally formed with the side walls of the casing as clearly shown in Fig. 2 of the drawing. To maintain the pivot pin or shaft 21 in position from longitudinal movement relative to the casing 1 the latter may be provided with threaded openings opposite the ends of the pivot pin or shaft 21 and in which may be threaded the screw plugs 21'. These plugs may operate as thrust means for conveniently maintaining the pivot pin or shaft 21 in place

but when removed permit the ready insertion and withdrawal of the shaft 21.

The main valve 15 is centrally cupped or depressed toward the inlet as at 23 throughout the major portion of its area and is provided on its outlet side with a lug 24, preferably integral therewith, which is adapted to act as a stop for the valve 15 in its completely open position. Within the cupped portion is located an abutment projection 25 which extends toward the outlet 3 and which is of utility for a purpose hereinafter more fully disclosed.

For the purpose of giving an alarm when the main valve 15 swings to open position there is provided an auxiliary valve 26 adapted to operate with an auxiliary valve seat 27 preferably in the form of a removable bushing suitably secured in the partition 10 as by screw threads 28 at one side of the valve 15 substantially on a diameter of the main valve 15 lying parallel to the axis of the pivot shaft 21, the purpose of such location of the valve 26 hereinafter more fully appearing.

The wall of the casing 1 is enlarged at a side thereof as at 29 within which is located a transverse bore or passage 30 which extends to both sides of the casing, the ends of said bore being suitably threaded so that a pipe connection may be made therewith from either side of the casing as convenience may dictate, the other end of the bore being accordingly suitably closed as by a screw plug 30'. Communication is had between the bore 30 and the port of the auxiliary valve seat 27 by another bore passage 31 suitably cored in the annular portion of the partition 10. In this fashion communication is had from the chamber of the casing 1, when the auxiliary valve 26 opens, to the exterior of the casing by way of the passages 31 and 30 and through which a part of the extinguishing fluid is adapted to flow to the alarm controlling mechanism connected to the bore 30 by means of a pipe or conduit 45. The end of the auxiliary valve seat 27 that is not provided with threads, is exteriorly formed with a truncated cone as at 32 and terminates in a comparatively flat annular surface 33 coaxial with the auxiliary valve 26 when the latter is in position against the seat 27. The valve 26 is in the form of a circular flat disk and is freely movable in the sleeve 34 so that one of its flat surfaces may be readily engaged against the auxiliary valve seat 27. The sleeve 34 is in the form of a hollow cylinder suitably threaded on its outer surface to be adjustably secured in a cylindrical enlargement 35 integrally provided at the end of the cross arm 36, a lock nut 37 being used to maintain the sleeve in secured position. The sleeve is also provided at one end with an inwardly projecting marginal flange 130

38 adapted to engage against the marginal portion of the inner flat surface of the auxiliary valve 26 for the purpose of moving the latter from its seat 27 at a predetermined time after the start of the opening of the main valve 15, and the other end of said sleeve is provided with an apertured screw plug 39, arranged to prevent the escape of the valve 26 upon its rearward movement from the valve seat 27. The aperture provided within the plug 39 permits the fluid in the chamber of the casing 1 to normally enter the sleeve 34 into contact with the auxiliary valve in order to seat it or hold it seated against the auxiliary valve seat 27. The exterior end of the plug 39 is also of a shape suitable to receive a tool by which to remove the plug as desired or when necessary. The sleeve 34 may be so adjusted in the enlargement 35 that the flange 38 may be normally spaced away from the inner surface of the valve 26 when the latter is seated against the seat 27 when the main valve is in its closed position, such space providing for a certain amount of "lead" found advantageous in this type of alarm valve. Having such a "lead," any conditions that would act upon the main valve to merely slightly open it will not effect an opening of the valve 26, while on the other hand, upon a complete opening of the main valve 15 the opening of the auxiliary valve is, in accordance with the lead given it, retarded in a certain time relation with the opening of the main valve.

As heretofore stated the enlargement 35 is integrally formed at the end of the cross arm 36. This cross arm is normally disposed transversely and adjacent the central portion of the outlet side of the main check valve 15 in a substantially parallel relation to the axis of the pivot 21 and is provided with a laterally extending abutment 40 which normally engages or abuts against the lug or abutment 25 on the main valve 15. The cross arm is preferably provided with a laterally extending arm 41 the outer end of which is provided with a relatively long bearing member or hub 42 suitably fitting, for pivotal action, over the pivot shaft 21 for a sufficient distance to give adequate rigidity to the construction whereby the cross-arm will be maintained in its parallel relation to the axis of the shaft 21 irrespective of the angular movement of the cross-arm 36 and its connected parts about such axis. The arms 36 and 41 may be provided with reinforcing webs 36' and 41' in giving the device added rigidity.

From the foregoing it is apparent that the construction and arrangement of the parts are such that in the operation of the device the sleeve 34 surrounding the auxiliary valve 26 moves in unison with the main valve 15 and that the adjusting feature, providing for a certain amount of "lead" for the valve 26, permits within prescribed limits, the retardation of opening of the auxiliary valve 26 with respect to the opening of the main valve 15.

If, however, it be desired, the sleeve may be adjusted so that both valves may open practically simultaneously. While the sleeve 34 is adjusted to permit the main valve 15 to open slightly in advance of the auxiliary valve 26 the latter is held against its seat by the fluid pressure in the casing, during the initial movement of the main valve 15 until the arms 36 and 41, as well as the sleeve 34, be sufficiently moved, by reason of the contact of the abutment projection 25 against the abutment 40 for the purpose of carrying the flange 38 into engagement with the valve 26. A further movement in the same direction of the parts above enumerated coördinately acts to lift the auxiliary valve 26 from its seat 27 and permits the entrance of the fluid from the chamber of the casing 1 into the passages 30 and 31 and the conduit 45 leading to the alarm controlling mechanism connected thereto. When the main valve is in its completely open position the lug 24 engages against the lug 43 in the casing.

The parts are so arranged that upon the removal of the cover or bonnet 13 convenient access may be had to all of the elements or parts contained within the casing so that the same may be conveniently adjusted, removed or replaced as may be desired or found necessary.

It will be noted that in this device the auxiliary valve is located at one side of the main valve 15 and in a line passing transversely, substantially through the center, of the valve and lying parallel to the axis of the shaft 21. This arrangement is followed in order that the opening of the auxiliary valve may be proportionately smaller than the movement of the forward end 44 of the main valve 15 upon the opening thereof. This is an important advantage where conditions exist that tend to temporarily open the main valve, such as "water-hammers" and other similar effects. In the prior art structures where the auxiliary valve is located at substantially the same distance from the axis, about which it rotates, as the forward end of the main valve, it is obvious that for any movement of the main valve there is a like movement of the means acting upon the auxiliary valve. If, however, a certain amount of "lead" be necessary in the prior art structures for a certain proper operation of the auxiliary valve it will be observed that in the present invention about one half of that amount of "lead" is required to effect the same result. The structure of the present invention has, therefore, a greater range of adjustment for any

amount of opening of the main valve. By also locating the auxiliary valve proximate to but out of the direct path of the main current of the extinguishing fluid through the main valve, the instant of the flow of such fluid to the alarm controlling means, is more accurately timed in relation to the effective opening of the main valve. The auxiliary valve is instantly operated at the 10 end of the "lead" given it so that a greater degree of sensitiveness in operation is obtained in its connection with the alarm controlling mechanism.

In operation the main and auxiliary valves 15 15 and 26 are normally closed but upon the opening of a sprinkler head caused by a fire or similar condition the main check valve 15 will completely open and carry with it the auxiliary valve 26 from the port of the 20 passage 31 whereupon a full flow of extinguishing fluid occurs through the casing 1 and a substantial flow of fluid through the passages 30, 31 and 45 to the alarm controlling mechanism. The auxiliary valve 25 may be adjusted so that it will open at a predetermined interval of time after the beginning of the opening of the main valve so that by the time the main valve is completely opened and the auxiliary check valve 30 is completely raised from its seat the full flow of fluid through the casing 1 will immediately be effective to cause a substantial flow of a portion thereof through the passages above mentioned. If, however, on the 35 other hand the main check valve were to be opened merely temporarily by reason of "water-hammers" or from other causes similar thereto, such opening would not be sufficient to raise the auxiliary valve from its 40 seat since the means tending to raise the same would merely operate within the extent of the "lead" given it by the adjustment previously determined upon so that no fluid 45 would be permitted to flow to the alarm control means.

While I have herein disclosed one embodiment of my invention it is to be understood, however, that the latter is not to be limited to the particular details herein described and 50 illustrated upon the accompanying drawing but that the same comprehends any other and all equivalent devices as do not depart from the spirit of my invention and the scope of the appended claims.

Having thus described my invention what 55 I claim as new and desire to secure by Letters Patent is:

1. In an alarm check valve comprising a casing having inlet and outlet passages and 60 a main check valve pivotally supported therein, the combination of an auxiliary check valve located in said casing and provided with an adjustable sleeve, a valve freely movable therein, an auxiliary valve

seat located in said casing adjacent to the 65 seat of said main check valve, passages provided within said casing communicating with said auxiliary valve and the exterior of said casing, an arm for said auxiliary valve extending over and contacting with 70 said main check valve, said arm pivotally mounted upon the same axis as the main check valve, said auxiliary valve and said auxiliary valve seat being located at a substantially shorter distance from said axis 75 than the outer portion of said main valve whereby the opening of said auxiliary valve is proportionately smaller than that of the portion of said main valve remotely located from said axis. 80

2. In an alarm check valve comprising a casing including inlet and outlet passages and a main check valve pivotally supported therein, the combination of an auxiliary valve, means extending over said main valve and connecting said auxiliary valve to the pivot of said main valve for pivotally supporting said auxiliary valve in said casing upon said pivot, an auxiliary valve seat provided in said casing and communicating 90 with the exterior thereof, means carried by said first mentioned means for adjusting said auxiliary valve with relation to said seat whereby said auxiliary valve opens at a predetermined time subsequent to the start 95 of the opening of said main valve, said auxiliary valve and said auxiliary valve seat being located adjacently at one side and substantially in the same plane of said main valve and at a point substantially midway 100 between parallel lines tangent to said main valve and lying in parallel relation to the pivot of said main valve.

3. In an alarm check valve comprising a casing having an inlet and an outlet, the 105 combination of a main check valve positioned in said casing, an auxiliary check valve also positioned in said casing adjacent, at one side of, and substantially in the plane of said main check valve, a pivot shaft 110 in said casing, an arm on said main valve and an arm on said auxiliary valve, said arms being independently and loosely mounted on said pivot shaft to have independent pivotal movement thereon, and means on said main check valve adapted to engage the arm of said auxiliary check valve for moving said arm upon movement of said main check valve. 115

4. In an alarm check valve comprising a 120 casing having alined inlet and outlet passages, the combination of a main check valve, an auxiliary check valve located to one side of said main check valve, a pivot shaft, arms connected to said main check 125 valve and said pivot shaft, an arm connected to said auxiliary valve, overlying said main check valve and independently con-

nected to said pivot shaft, whereby the opening movement of said main check valve is imparted to said auxiliary check valve.

5. In an alarm check valve comprising a casing having aligned inlet and outlet passages, the combination of a main check valve, an auxiliary check valve, a pivot shaft, spaced arms connected to said main check valve and said pivot shaft, an auxiliary arm located between said spaced arms with one end of said auxiliary arm pivotally connected to said pivot shaft and the other end thereof overlying the central por-

tion of said main check valve, a laterally extending arm connected to the overlying end 15 of said auxiliary arm with the free end of said laterally extending arm overhanging the periphery of said main check valve and means carried by said free end of said laterally extending arm adapted to open said auxiliary check valve upon a substantial opening of said main check valve.

In witness whereof, I have hereunto set my hand this 27th day of October, 1919.

LEROY M. LEWIS.
